(57) **CLAIM**

The ornamental design for a computer security lock, as shown and described.

DESCRIPTION

FIG. 1 is a perspective view of a computer security lock showing my new design;

FIG. 2 is a front view thereof, the rear view being invisible in ordinary use of the computer security lock;

FIG. 3 is a top view thereof, the bottom view (of the claimed subject matter) being a mirror image thereof; and,

FIG. 4 is a side view thereof, the other side view being a mirror image thereof.

The broken lines in the drawings illustrate environmental structure of the computer security lock that form no part of the claimed design.
